UNITED STATES PATENT OFFICE.

SAMUEL CARD, OF EAST PROVIDENCE, RHODE ISLAND.

SEPARATOR FOR SPINNING-FRAMES.

1,352,657.

Specification of Letters Patent. Patented Sept. 14, 1920.

Application filed February 26, 1920. Serial No. 361,391.

To all whom it may concern:

Be it known that I, SAMUEL CARD, a citizen of the United States, residing at East Providence, in the county of Providence and State of Rhode Island, have invented certain new and useful Improvements in Separators for Spinning-Frames, of which the following is a specification, reference being had to the accompanying drawings.

10 This invention relates to spinning frames for spinning cotton or worsted, and particularly to separators, that is devices designed to be used in connection with the spindles of the spinning frame for the purpose of preventing any ballooning of the yarn.

The general object of my invention is to provide a separator of a very simple character which is relatively light, cheap, which will remain cleaner for a longer time than the ordinary separators now in use, and which will not impede to as great a degree the free movement of the yarn and, therefore, not require so much power to be used in rotating the spindles.

25 A further object is to provide a separator consisting of a longitudinally extending rod mounted upon the ring rail and moving therewith, which rod is common to a plurality of spindles, this rod being so disposed that the yarn will strike the rod and thus be prevented from ballooning and the yarns from sticking to each other.

Other objects will appear in the course of the following description.

35 My invention is illustrated in the accompanying drawings, wherein:—

Figure 1 is an elevation of a spinning frame with my separator applied thereto;

Fig. 2 is a section through the spinning frame showing an end view of the separator and its supports.

Referring to these drawings, 10 designates a portion of a spinning frame of any usual or suitable construction and having the usual spindles 11 and carrying the usual whirls 12. Mounted to reciprocate vertically is the usual ring rail 13 having large perforations through which the bobbins pass, as usual. All of these parts are of any usual or suitable construction and form no part of my invention.

50 My improved separator comprises a longitudinally extending rod 14 of relatively small diameter which is mounted upon suitable supports at the ends of the ring rail. These supports 15, as illustrated, are ver-

tically slotted, as at 16, and are in the form of posts having their lower ends reduced in diameter and disposed through short slots and screw-threaded for the reception of 60 binding nuts 17. The rod 14 at its extremities is screw-threaded, as at 18, and a pair of binding nuts 19 are disposed on each side of the rod which will clamp against the flat sides of the supports 16. Thus it will be 65 obvious that the height of the separator 14 may be adjusted to suit the length of the bobbin. The slot 16 extends to a distance of $\frac{1}{2}$ " from the ring rail and upward to a distance of $\frac{1}{2}$ " below the top of the upper 70 end of the post or supporting member 15.

In the operation of this device, the separator operates to stop the yarn from ballooning and the yarns from sticking together and, of course, traverses up and down 75 with the ring rail as the bobbin is filling. It operates in the ordinary manner of a separator, that is the yarn strikes the separator and ballooning is prevented and the yarns are kept from whipping together. 80 As the rod is highly polished, it is obvious that it will exert the least possible friction upon the yarns. There will be no danger of the yarns catching and breaking.

While I have illustrated a construction 85 which I have found to be thoroughly practical for this purpose, yet it is obvious that many changes might be made in the details of this construction and arrangement of the parts without departing from the spirit of 90 the invention.

It is to be understood, of course, that I have only illustrated the spinning frame, the spindles, and the ring rail diagrammatically and have not attempted to show these 95 parts in detail, as they are well known and my invention does not relate to the details of construction of these parts.

I claim:—

1. In a spinning machine, the combination 100 with a series of spindles and a vertically traversing ring rail through which the spindles pass, of a separator comprising a longitudinally extending rod disposed to one side of the spindles and extending parallel to the 105 ring rail, and supports for the rod mounted upon the ring rail and engaging the opposite ends of the rod.

2. In a spinning machine, the combination 110 with a series of spindles and a vertically traversing ring rail through which the spindles pass, of a separator comprising a longi-

tudinally extending rod disposed to one side of the spindles and extending parallel to the ring rail, and supports for the rod mounted upon the ring rail and engaging the opposite ends of the rods, said supports being vertically slotted and the rod being vertically adjustable in said slot.

3. In a spinning machine, the combination with a series of spindles and a vertically traversing ring rail through which the spindles pass, of a separator comprising a longitudinally extending rod disposed to one side of the spindles and extending parallel to the ring rail, and supports for the rod mounted upon the ring rail and engaging the opposite ends of the rod, said supports being vertically slotted and the rod being screw-

threaded at its opposite ends and extending through said slot and provided with clamping nuts on each side of the support whereby the rod may be held in adjusted positions. 20

4. The combination with a vertically movable ring rail having transverse slots, and spindles passing through apertures in the ring rail, of a separator comprising supports mounted for adjustment in the slots of the ring rail and vertically slotted, and a longitudinally extending rod disposed in said slots of the supports and mounted for vertical adjustment therein. 25

30 In testimony whereof I hereunto affix my signature.

SAMUEL CARD.
